UNITED STATES PATENT OFFICE.

JOSEPH RUBY, OF BECKLEYSVILLE, MARYLAND.

VETERINARY INSTRUMENT.

SPECIFICATION forming part of Letters Patent No. 453,508, dated June 2, 1891.

Application filed March 18, 1891. Serial No. 385,527. (No model.)

To all whom it may concern:

Be it known that I, JOSEPH RUBY, a citizen of the United States, residing at Beckleysville, in the county of Baltimore and State of Maryland, have invented a new and useful Veterinary Instrument, of which the following is a specification.

The invention relates to improvements in veterinary instruments.

10 The object of the present invention is to provide a veterinary surgical instrument adapted to conveniently and effectively administer medicines to animals without liability of injuring the mouth or throat of an 15 animal or being bit by the same.

The invention consists in the construction and novel combination and arrangement of parts hereinafter fully described, illustrated in the accompanying drawings, and pointed 20 out in the claims hereto appended.

25 In the drawings, Figure 1 is a perspective view of an instrument constructed in accordance with this invention, a powder being shown in proper position preparatory to injection. Fig. 2 is a longitudinal sectional view. Fig. 3 is a detail view showing more clearly the construction of the spring-clamp at the end of the barrel.

30 Referring to the accompanying drawings, 1 designates a pistol, consisting of a barrel 2, a handle 3, and firing mechanism of the ordinary construction. Arranged within the barrel near the outer ends of the same is a spiral spring 4, which has one end bearing against 35 a shoulder 5, and the outer end of the spring engages a plunger 6, which is adapted to expel a powder or a ball and throw the same down the neck of an animal, and which is connected by a rod 7 with the hammer 8 of 40 the pistol, whereby when the hammer is cocked the spiral spring 4 is compressed and the plunger is drawn within the barrel and is adapted to be thrown forward by the spring when the trigger 9 is pulled. The spiral 45 spring 4 is sufficiently strong to discharge the pistol and throw the powder, and the main-spring 10 may be omitted, if desired; but in cases where the medicine is sticky and is apt to cling to the pistol and is to be administered 50 to cattle it is often advantageous to employ a mainspring. The rear end of the rod 7 is provided with a hook 11 and engages an eye 12

of a pin 13, arranged in an opening of the hammer and being threaded and provided with a nut 14, arranged at the back of the 55 hammer and engaging the same and securing the pin thereto.

The medicine to be administered, when a powder, is wrapped in tissue paper, and when a liquid is put up in the shape of balls in a 60 soluble shell and is placed between the elastic piece 15, which is centrally secured to the plunger and has its ends secured to curved spring-arms 16, which are preferably composed of plates of sheet metal, and the ends 65 of the rubber are secured between the ends of the same. The arms 16 are connected with the barrel by springs 17, which have their inner ends secured to the barrel and their outer ends secured to the arms. As the plunger 70 is drawn inward by the cocking of the pistol the spring-arms are brought together and they clamp the medicine until the plunger is released at the firing of the pistol. The mouth of the animal is opened and the 75 tongue pulled forward and turned to one side in the usual manner, and then the instrument is inserted until the medicine is at the root of the tongue, and it will be found most convenient to hold the pistol horizontally 80 with the handle turned upward, and by moving the hand slightly to one side the mouth is exposed to full view.

In order to enable the mainspring of the pistol to be adjusted and removed from engagement with the hammer without removing the handle-plates, a metal block 18 is provided and is swiveled to a screw 19, having its head arranged outside the handle and adapted to be readily turned to raise and 85 lower the spring and adjust its tension, and the metal block 18 is provided with a recess 90 20, which receives the lower rear end of the spring.

What I claim is—

1. A veterinary instrument comprising the pistol, the plunger arranged within the barrel, the rod connecting the plunger and the hammer, the curved arms arranged at the end of the barrel, and the elastic piece 15, 100 centrally secured to the plunger and having its ends connected to the arms, substantially as described.

2. A veterinary instrument comprising the

pistol having its barrel provided with the shoulder 5, the spiral spring arranged within the barrel and having its inner end bearing against the shoulder, the plunger arranged 5 within the barrel and being engaged with the outer end of the spring, the rod connecting the plunger and the hammer, and the spring-arms secured to the outer end of the barrel and adapted to hold medicine, substantially 10 as described.

3. In a veterinary instrument, the combination of the pistol, the screw 20, arranged at the butt of the pistol, and the metal block provided with a recess to receive the rear end 15 of the mainspring and secured to the screw, substantially as described.

4. The barrel and the plunger therein, combined with the elastic piece 15, centrally se-

cured to the plunger, the curved spring-arms 16, to which the ends of the elastic piece are 20 secured, and the springs 17, attached to the barrel and connected to the ends of the arms 16, substantially as described.

5. The barrel and the plunger therein, combined with the elastic piece 15, centrally secured to the plunger, and the curved spring-arms 16, said arms being composed of plates 25 of sheet metal which are flexibly connected to the barrel, substantially as described.

In testimony that I claim the foregoing as 30 my own I have hereto affixed my signature in presence of two witnesses.

JOSEPH RUBY.
